UNITED STATES PATENT OFFICE.

ARTHUR E. POHLMAN, OF WEST ALLIS, WISCONSIN.

MINIATURE-AEROPLANE CONSTRUCTION.

Application filed March 24, 1923. Serial No. 627,315.

To all whom it may concern:

Be it known that I, ARTHUR E. POHLMAN, a citizen of the United States, and a resident of the city of West Allis, in the county 5 of Milwaukee and State of Wisconsin, have invented certain new and useful Improved Miniature-Aeroplane Constructions; and I do declare the following to be a clear, exact, and complete description thereof, such as 10 will enable others skilled in the art to which the invention relates to make and use the same, reference being had to the accompanying drawing, as illustrating a construction in which the invention has been embodied 15 and showing also the succession of operations pertaining to such construction.

The invention relates to a miniature aero- 20 plane construction and resides in such construction, as well as in the simplified opera- tions and reduction in the number of parts involved in its manufacture. The purposes 25 of the invention are the production of a toy aero- plane of novel form, which may be easily manipulated, operating smoothly, and 30 by means of a shaped propeller which is rapidly rotated by the pressure of the atmosphere, will produce a sound simulating that 35 of aeroplanes existing in practical form.

Aeroplanes of this type are known, but 30 their cost of construction is great by reason of the many operations required in the manufacture and assembly of the parts, as well as the time required for such assembly. My 35 invention overcomes the objections which have been encountered heretofore in similar structures and I am able to produce a miniature aero- plane with fewer parts.

The polygonal body or fuselage is formed 40 from a single piece which is blanked from a sheet of suitable material, an appropriate contour being imparted to such blank at the time of its production. Coincidentally with the production of the fuselage blank the rudder and stabilizing tail fins are produced 45 in the form of extensions of certain of the side members of the fuselage. The structural elements constituting these parts are always, therefore, in their proper relative positions, so that the operation of assem- 50 bling involves merely the shaping of the fuselage on the lines connecting the parts, and by simple further operations securing such parts in position.

The guiding and sustaining planes to- 55 gether with the standards connecting them in a bi-plane are likewise produced in a

single blanking operation, and in the assembly it is necessary only to bend the connected parts into proper positions and secure their attachment. 60

In the practice of my invention, I have, therefore, eliminated many of the more tedious operations required in assembling the older structures, and have greatly facilitated the manufacture of devices of this 65 class, and in a much more economical manner.

Other details of the invention will be referred to hereinafter, and the novelty will be pointed out in the appended claims. 70

In the drawing attached hereto:

Figure 1 is a perspective view of a mini- 75 ature aero- plane constructed in accordance with my invention.

Fig. 2 is a plan view showing the contour 80 of the blank which is designed to form the fuselage, and also the rudder and fins, together with some other features which will be hereinafter described.

Fig. 3 is a plan view of a blank embody- 85 ing the wings of a bi-plane construction, together with the posts or standards and fastening devices, the latter being designed to secure the parts in assembled position.

Fig. 4 is a plan view of a blank designed 85 to be shaped and secured at the under side of the device, in simulation of the ground wheels.

Fig. 5 illustrates the formation of the 90 back-bone which extends longitudinally of the fuselage, and at the front thereof forms the pivot for the propeller.

Fig. 6 is a plan showing the contour of 95 the blank from which the propeller is shaped.

Fig. 7 shows in outline a blanked figure, which may be mounted upon the aero- plane for ornamental purposes or effecting fur- 100 ther stabilizing of the same.

Referring to the drawings, the assembled 100 miniature aero- plane is composed of the structural elements illustrated in the other figures. The blank 10, Fig. 2, is suitably contoured in one operation to produce in one piece the four sides 11, 12, 13, and 14 105 of the fuselage, the points of connection of the sides being indicated by the short, parallel broken lines, and which constitute the lines on which the blank is to be folded into shape. The sides referred to taper toward 110 the front and toward the rear, so as to produce a tapering body which in the con-

struction shown is squared in any cross section. The part 12 has formed integrally therewith a portion 15 which constitutes the rudder of the aeroplane, and the part 14 is likewise extended so as to form the stabilizing tail fins 16. The part 11 is provided with a reduced portion 17 at the front and a like portion 18 at the rear, and the parts 12 and 14 have like reduced projections 19 and 20 at the front. The part 13 is provided with integral binding pieces 21 at the front and 22 at the rear, for purposes which will be described.

Perforations 23 and 24 are provided near the central portion of the part 12 and like perforations 25 and 26 are similarly located with reference to the part 14, which latter is also provided with a perforation 27, designed to be entered by the projection 28, extending laterally from the part 11. The fin is perforated at 29 for the reception of a projection 30 depending from the rudder.

The blank shown in Fig. 3 comprises the upper wing 31 and the lower wing 32, connected by members 33 and 34, which form supporting standards. Like portions 35 and 36 extend oppositely from the wing 31. The wing 32 is perforated at 37, 38, 39, and 40. The remaining features of the blank shown in Fig. 3 will be described.

In assembling the device, the fuselage blank 10 is folded on the dotted lines before referred to so as to produce a squared central body 41, the projection 28 on the part 11 being passed through the perforation 27 in the part 14, and bent so that the end of the projection will lie parallel with the part 14. In this formation the rudder 15 lies parallel with the stabilizing fins 16, but the rudder is turned at an angle of 90° at the point of its connection with the part 12, so that the rudder will stand normal to the fin. The projection 30 is passed through the perforation 29 in the fin 16, and the ends of the projection turned so as to lie parallel at the under side of the fin, the projection being split to permit the fastening to extend in opposite directions. The back-bone 42, provided at its rear end with an angular projection 43, is passed into the open front end of the fuselage, and such projection 43 is seated in a perforation 44 formed in the fin 16. The tapering rear ends of the parts 11 and 13 are then brought together about the back-bone, which is already embraced by the tapering rear ends of the parts 12 and 14, so as to form a compact structure of the parts. The binding piece 22 is wrapped around the parts, including the projection 18, which are thus brought into close relation, the ends of the binding piece being passed through the perforation 45 in the rudder 15 so as to complete the assembly at the rear of the fuselage.

The wings 31 and 32 and the standards 33

to 36 are folded at right angles at the points of connection, so that the wings will appear superposed as shown in Fig. 1, and sustained in separated position by the said standards. The free ends of the standards 35 and 36, extending from the wing 31, are entered in the perforations 39 and 40 in the wing 32, and turned so as to lie against the wing 32 and secure the parts in the manner shown in Fig. 1. The standards 33 to 36 are provided with laterally extending parallel portions 46, 47, 48, and 49 which may be bent at an angle so as to impart rigidity to the said standards. The circular ends 50 and 51 of the blank shown in Fig. 4 are bent at right angles to the central part 52, and stand in parallelism with each other. Projections 53 and 54, punched out of the central portion 52 are entered in the perforations 37 and 38 of the lower wing 32, the ends of such projections being turned to lie in parallelism with the wing 32, and thus attach the ground wheels to the structure. An ordinary cotter pin 55 may be passed through central openings in the wheels 50 and 51 to simulate the axle of the wheels.

The front end of the partially assembled fuselage is inserted between the wings, and the projections 56 and 57 on the wing 32 are passed through the perforations 25 and 26 in the part 14, and clinched as before. Projections 58 and 59, which may be reinforced, as are the standards 33 to 36, extend oppositely from the wing 31.

These projections are adapted to be bent so as to stand normal to the plane of the wing 31, at the under side thereof and the free ends of the projections are entered in the perforations 23 and 24 in the part 12, and bent upon the inside of the fuselage so as to lie parallel with the said part 12.

The forward tapering ends of the parts 11, 12, 13 and 14 are now brought into close engagement with the back-bone 42, and the binding strip 21 attached to the part 13 is wrapped around the projections 18, 19, and 20 on the parts 11, 12, and 14, to complete the structure. The propeller 60 is now placed upon the forwardly extending end of the back-bone 42 so as to rotate freely thereon under atmospheric pressure when flight is given to the aeroplane. The bringing together of the tapering ends of the parts 11, 12, 13 and 14, in the manner hereinbefore described, constitute the fuselage as a body which is polygonal in cross-section, and which tapers towards its opposite ends, that is, toward its front and toward its rear.

The miniature aeroplane is suspended in a state of equilibrium by a cord 61 attached at a point of balance, which may be the part 59. The cord 61 will be of suitable length to permit the free end thereof to be held by the hand of the person, or at

the end of a stick, and may be whirled about the body of the person, the free end of the cord 61 being held above the head. The device operates with a pleasing effect and is 5 very attractive inasmuch as the whirring produced by the propeller simulates very closely that of the commercial planes.

An ornamental figure 61', constituted of the blank shown in Fig. 7 may be attached 10 to the wing 31 for purposes of ornamentation. The location with relation to the wing may be varied at pleasure and the figure may be in any desired form. In certain locations it will assist in maintaining the 15 equilibrium of the device. The part 61' may be provided with a clamp, as shown, for effecting a frictional engagement with the edge of the wing, sufficient to retain the said part in any of the positions in which it may 20 be placed. If arranged in line with the rudder, the upstanding figure will assist in maintaining the equilibrium in a greater degree. If arranged at a point at one side 25 of the longitudinal central vertical plane of the fuselage, as in the manner shown, it will, dependent upon its particular arrangement, assist in stabilizing the movement of the device more exactly in its circular path.

30 As indicated hereinbefore, the device will be produced from any suitable material in sheet form, and although I prefer to use thin metal sheets, I do not desire to be limited to such material. Ordinarily, the 35 sheet material employed in the production of the fuselage will possess sufficient inherent rigidity to maintain the sides in proper position. But in case very thin metal is used, I may impart rigidity to the parts 11, 40 12, 13 and 14, and increase the ornamental appearance, by turning the edges thereof so as to form ribs or flanges 62, to reinforce the said parts and prevent deflection from the planes in which they extend.

45 Means other than those shown may be used for securing the parts when assembled.

Having thus described my invention, what I claim and desire to secure by Letters Patent of the United States, is:

50 1. A miniature aeroplane, comprising a polygonal fuselage tapering towards its ends and a rudder and stabilizing fin inte-

gral therewith, with means on the rudder for effecting locking engagement with the fin, and means integral with the fuselage for binding the tapering ends of the fuselage.

2. In a miniature aeroplane, a polygonal fuselage tapering towards its ends and a rudder and stabilizing fin integral therewith, with means for effecting locking engagement between the rudder and fin, and means integral with the fuselage for binding the tapering ends of the fuselage, in combination with wings attached and supported in separated position upon the fuselage by 60 standards integral with the wings.

3. In a miniature aeroplane of the bi-plane type, upper and lower wings connected and supported in separated position upon the fuselage by standards integral with the 70 wings, in combination with a fuselage fixed between the wings and having a rudder and stabilizing fin integral with the fuselage.

4. A miniature aeroplane comprising a polygonal fuselage tapering towards its ends and a rudder and stabilizing fin integral therewith, a longitudinally extending back-bone, and means for binding the tapering ends of the fuselage about the back-bone.

5. In a miniature aeroplane, a fuselage and a rudder and stabilizing fin integral therewith, wings supported upon the fuselage, and a figure changeable as to its location mounted upon one of the wings and 85 adapted to cooperate with the rudder to further direct the aeroplane in its movement.

6. In a miniature aeroplane, and integral hollow fuselage polygonal in cross section formed with sides tapering to its opposite end points and with a rudder and stabilizing fin also integral therewith, means formed on the rudder for locking the same in relation to the fin, and means for binding the said tapering sides to produce tapering ends 90 in the fuselage, in combination with wings supported by the fuselage.

In testimony whereof, I have signed my name at Milwaukee, Wisconsin, this 17th day of March, 1923.

A. E. POHLMAN.
